UNITED STATES PATENT OFFICE.

WILLIAM J. McCURDY, OF NEW BRUNSWICK, NEW JERSEY, ASSIGNOR TO
THE NEVERSLIP MANUFACTURING COMPANY, OF SAME PLACE.

DESIGN FOR A FOOT-GUARD FOR INTERFERING HORSES.

SPECIFICATION forming part of Design No. 32,017, dated December 19, 1899.

Application filed November 22, 1899. Serial No. 737,962. Term of patent 14 years.

To all whom it may concern:

Be it known that I, WILLIAM J. McCURDY, a citizen of the United States, residing at New Brunswick, in the county of Middlesex and State of New Jersey, have invented and produced a new and original Design for a Foot-Guard for Interfering Horses; and I do hereby declare the following to be a full, clear, and exact description of the same, reference 5 being had to the accompanying drawings, forming a part thereof.

Figure 1 is a perspective view of a foot-guard, showing my new design. Fig. 2 is a vertical section of the same.

10 As shown in the drawings, the leading or material feature of my design consists of a segment of a ring A, tapering toward its ends b, but convex and semicylindrical in cross-section, as shown at c. The inner face d of said 15 segment of ring is substantially vertical.

20

There is projecting laterally from said inner face d a thin shelf E, wider than the segment of a ring A, but integral therewith. Said shelf is slightly longer than the portion A. It has its ends rounded, and its top surface has a 25 series of grooves or corrugations e crossing each other from one end of said shelf to the other, the whole being molded together of elastic material, as rubber.

Having described my invention, what I 30 claim as new, and desire to secure by Letters Patent, is—

The design for a foot-guard for interfering horses as herein shown and described.

In testimony whereof I affix my signature 35 in presence of two witnesses.

WILLIAM J. McCURDY.
